DEVICE FOR FITTING CAPS UPON SAFETY PIN SHANKS.

FILED JUNE 3, 1921.

Patented Jan. 9, 1923.

1,441,749

UNITED STATES PATENT OFFICE.

HANS PRYM, OF STOLBERG, GERMANY.

DEVICE FOR FITTING CAPS UPON SAFETY-PIN SHANKS.

Application filed June 3, 1921. Serial No. 474,862.

To all whom it may concern:

Be it known that I, HANS PRYM, manufacturer, a subject of Germany, and residing at Stolberg, Rheinland, Germany, have invented certain new and useful Improvements in Devices for Fitting Caps Upon Safety-Pin Shanks, of which the following is a specification.

The present invention relates to an apparatus for mounting and fastening the heads of safety pins on the shanks thereof. In apparatus hitherto used, the head is being carried to the preliminarily bent shank is loosely positioned and thus can not always be fastened in the desired position on the shank, thereby resulting in interruption to operation and a product which is not uniform.

This defect is completely overcome by the present invention in that the individual heads, on passing out of a guide, are taken up by a rotatable element which carries them into the vicinity of a pin shank, this element being so constructed that the heads can not move from their position with respect to the element during the movement.

Two exemplary embodiments of the subject of the invention are shown on the drawing, in which:

Fig. 1 is a longitudinal section through one embodiment with a rotatable roller in position for the reception of the heads;

Fig. 2 is a plan view thereof;

Fig. 3 is a longitudinal section with the roller in position after fastening the head.

Fig. 4 is an enlarged fragmentary section view of the second embodiment.

Referring now more particularly to the drawings in which similar reference characters indicate corresponding parts there is provided a rotatable roller n which is subject to the action of a draft or traction spring y^1 . This roller has an angular projection y , on which the pin shank d is bent. Below the roller is a slide n^4 which is moved reciprocally preferably by means of a lever n^5 and in its movement toward the right rotates the roller so that it assumes the position of Fig. 1, while on its movement to the left it releases the roller, so that the roller will be turned back by the action of the spring y^1 for a distance of 90° (Fig. 3).

The roller n is journaled in one end of a slide n^1 , which at its other end carries a roller n^2 , against which a lug or cam n^3 is applied. By means of the lug the slide n^1

with the roller n is moved to the right and then pulled back by a spring n^6 . A pressure member s is journaled in the roller n and a pressure bolt t is employed for pressing member s on the head k . Journaled in the slide n^1 is another slide v^3 , which carries a resiliently mounted mandrel v such mounting being preferably effected by means of a spring v^1 . This mandrel v serves for forcing out a jammed head, if the latter is not attached when a pin shank is out of alignment. Slide v^3 is reciprocated by means of a lever v^2 . d^1 represents a pin support and d^2 a roller which carries the pin shank d into the operative position.

This apparatus operates as follows:

In the position of Fig. 1 the roller n successively receives the heads k delivered from the guide trough a . The slide n^4 is now moved to the left by means of the lever n^5 , whereby the roller n is released, and rotated outwardly and downwardly to the extent of 90° under the action of the spring y^1 to the position shown in Fig. 3. At the same time as the slide n^4 is moved to the left the slide n^1 and roller n are moved to the right. During this movement of the roller n the head k positioned in the roller n receives the preliminarily bent shank d of the safety pin (Fig. 3). By means of the pressure members axially journaled in the roller n , through the pressure bolt t which may be actuated as desired, a powerful pressure is exerted on the heads k , whereby these are securely fastened on the shank d .

Simultaneously with the movement of the slide n^1 to the right, the slide v^3 is also moved to the right by means of the lever v^2 whereby the mandrel v subject to the action of the spring v^1 , is pressed into the opening w of the roller n and strikes the head, whereby the spring v^1 is compressed. If the head is properly mounted on the pin shank the mandrel v has no further action herein. If, however, the pin shank has not been aligned with the head, which prevents the head from being secured thereto, the striking of the head by the mandrel effects an ejection of the head from the roller.

After the heading operation the slide v^3 with the mandrel v are returned by means of the lever v^2 . At the same time the slide n^1 and the roller n are drawn back, and the finished safety pins are released. Simultaneously with the return movement of the slide n^1 , the slide n^4 is moved forward by

means of the lever n^5 , and the roller n is returned to its initial position for the reception of a new head, Fig. 1. In this position a new pin shank d is bent on the specially formed projection y , said shank d being carried into position by the roller d^2 . A tool g (Fig. 1) is adapted to be pressed on the shank to bend it at right angles corresponding to the form of the projection or lug, 10 wherein the slide n^4 serves as a support for the lug.

After the bending of the shank the pin support d^1 is moved upwardly to support the bent pin until termination of the heading operation (Fig. 3) and then is drawn downwardly (Fig. 3).

Omitting the lug y of the roller n^{10} , the shank d^{10} may be bent by a rotatable round member u^{10} which is independent of the roller n^{10} (Fig. 4). This member has a portion of semi-circular cross section serving for bending the pin, the flat side of which is directed upwardly. The shank d^{10} is inserted on the member u^{10} and then a vertically reciprocal punch q^{11} , attached to the machine shaft, is pressed thereagainst so that, as shown on Fig. 4, the front edge q^{11} of the punch comes into position laterally of the rotational axis of the member u^{10} approximately the thickness of the pin shank and does not interfere with the rotation of said member. The member u^{10} is then turned in the direction of the arrow for 90° , so that point l comes into position in point 35 l^1 . Thereby the free end of the shank d^{10} is bent, since the punch q^{11} , which serves as a support for the pin shank, prevents raising thereof. After the bending operation punch q^{11} again passes upwardly, and the member u^{10} is again drawn to the side and the roller n^{10} rotated to be shoved on the shank.

Having thus fully described the invention what is claimed and desired to be secured 45 by Letters Patent is:

1. Apparatus for mounting and fastening the heads of safety pins on the pin shanks, including in combination, a stationary guide for the heads of the pins, a support for the shanks of the pins, and a rotatably and slidably mounted element for successively receiving and rigidly supporting the heads and for carrying them towards the shank support so that they may be successively delivered.

2. Apparatus for mounting and fastening the heads of safety pins on the shanks thereof, including in combination, a guide for the heads of pins, a support for the shanks

of pins and a rotatably and slidably mounted roller having means formed therein for successively receiving pin heads from the guide so as to rigidly support the same so that the heads may be successively delivered on a pin shank on the shank support. 65

3. Apparatus as claimed in claim 1 wherein the element consists of a roller provided with a head receiving seat extending radially from the longitudinal axis thereof.

4. Apparatus in accordance with claim 1 70 wherein means is provided for the fastening of the head on the shank including a compression element journaled axially in the rotatably and slidably mounted element.

5. An apparatus in accordance with claim 75 1 wherein a spring actuated mandrel is directed radially against the element for forcing an unattached head from the element.

6. Apparatus in accordance with claim 1 80 wherein the element consists of a roller having a head receiving seat wherein the means for mounting the same consists of a slide in which the roller is journaled, another slide mounted in the first mentioned slide and a resiliently mounted ejecting mandrel in the 85 second slide.

7. Apparatus in accordance with claim 1 90 wherein the element is provided with an angular projection upon which a pin shank is adapted to be bent.

8. Apparatus for mounting and fastening the heads of safety pins on the shanks of said pins, including in combination, a stationary guide for the heads of the pins, a support for the shanks of the pins, a manually operable slide, a reciprocatable spring controlled slide mounted on the manually operable slide, a roller journaled in the last mentioned slide and provided with a head receiving seat, resilient means in connection with the roller for partially rotating the roller upon operation of the slide so that a pin head received from the guide will be carried toward the shank, a compression element journaled axially in the roller for applying the head to a pin shank, a third manually operable slide mounted in the roller carrying slide, and a spring pressed head and ejecting mandrel mounted in the last mentioned slide, substantially as and 100 for the purposes set forth.

In testimony whereof I hereunto affix my signature in presence of two witnesses.

HANS PRYM.
